UNITED STATES PATENT OFFICE.

HENRY WARDEN, OF PHILADELPHIA, PENNSYLVANIA.

TUBE-SHEET FOR STEAM-BOILERS, &c.

SPECIFICATION forming part of Letters Patent No. 352,380, dated November 9, 1886.

Application filed August 23, 1886. Serial No. 211,690. (No model.)

To all whom it may concern:

Be it known that I, HENRY WARDEN, a citizen of the United States, residing in Philadelphia, Pennsylvania, have invented certain Improvements in Tube-Sheets for Steam-Boilers, Feed-Water Heaters, &c., of which the following is a specification.

One object of my invention is to so construct a tube-sheet for steam-generators as to prevent straining of the sheet or impairment of the joints of the tubes therewith, owing to expansion and contraction of said tubes, a further object being to so stiffen the tube-sheet that a less number of internal stays than usual will be required to retain the same.

In the accompanying drawings, Figure 1 is an end view of a boiler, feed-water heater, or analogous structure having a tube-sheet constructed in accordance with my invention; Fig. 2, a sectional view on the line 1 2 of the end portion of the structure, and Figs. 3 and 4 views illustrating modifications of the invention.

A represents part of the shell of a boiler, feed-water heater, or other structure in which my improved tube-sheet is used, this structure in the present instance being of cylindrical form, although it may be of different shape without departing from my invention.

B are the tubes, the ends of which are secured in the tube-sheet D by expanding them into openings formed in said sheet in the usual manner; but in carrying out my invention I form in the tube-sheet around one or more of the tube-openings, or around one or more groups of openings, a groove or corrugation, a, outside of which is an elastic portion, b, the preferable plan being to form a corrugation around each tube-opening and as close as practicable to said opening. This corrugation serves to stiffen the tube-sheet at and near each tube, so that when there is longitudinal movement of the end of the tube, due to expansion and contraction of the said tube, that portion of the tube-sheet immediately surrounding the tube moves with the end of the latter, the movement being permitted owing to the elastic portion b around each corrugation a, this portion preferably consisting of a flat space of sufficient area to insure the req-

uisite elasticity. Each tube is thus free to expand or contract independently of the other tubes of the structure without unduly straining the tube-sheet or causing leakage by impairment of the joint between the tube and sheet. The tubes may, however, be divided into groups, each with a circumscribing corrugation and surrounding elastic portion, as shown, for instance, in Figs. 3 and 4, or a single tube or group of tubes alone may have the circumscribing corrugation and outer elastic portion. The tube-sheet has in the present instance upper and lower man-holes, F and G, and in order to stiffen the sheet where these man-holes are formed each of said man-holes is surrounded by a corrugation, d.

In that portion of the tube-sheet above the tubes I form a series of corrugations, f, which serve to impart such stiffness to this portion of the sheet that the number of internal stays necessary in the structure may be very materially reduced.

I claim as my invention—

1. A tube-sheet one or more of the openings of which has a circumscribing corrugation, with elastic portion beyond the same, all substantially as specified.
2. A tube-sheet the tube-carrying portion of which comprises a number of divisions, each with one or more tube-openings, a circumscribing corrugation, and an elastic portion beyond the latter, all substantially as specified.
3. A tube-sheet each of the tube-openings of which has a circumscribing corrugation and an outer elastic portion beyond the latter, all substantially as specified.
4. The combination of the tubes with a tube-sheet, one or more of the tube-openings or tube-spaces of which has a circumscribing corrugation and an elastic portion beyond the same, whereby the tube-sheet is relieved from strain due to the uneven expansion and contraction of the tubes, all substantially as specified.
5. A tube-sheet having tube-openings and one or more man-hole openings with circumscribing corrugation, all substantially as specified.
6. A tube-sheet having one or more tube-openings or tube-spaces with circumscribing

corrugation and elastic portion beyond the same, and one or more man-hole openings, with circumscribing corrugation, all substantially as specified.

5 7. A tube-sheet having one or more tube-openings or tube-spaces with circumscribing corrugation and elastic portion beyond the same, and having corrugations in that portion in which there are no tube-openings, all substantially as specified.

In testimony whereof I have signed my name to this specification in the presence of two subscribing witnesses.

HENRY WARDEN.

Witnesses:

THOMAS M. KELLY,
HARRY SMITH.
